UNITED STATES PATENT OFFICE.

DAVID GEESNER, OF WORCESTER, MASSACHUSETTS.

SPOT-PROOFING MECHANISM.

1,157,773.

Specification of Letters Patent. Patented Oct. 26, 1915.

Application filed December 30, 1910. Serial No. 600,057.

To all whom it may concern:

Be it known that I, DAVID GEESNER, a citizen of the United States, and a resident of Worcester, in the county of Worcester and State of Massachusetts, have invented certain new and useful Improvements in Spot-Proofing Mechanism, of which the following is a specification.

My invention relates to improvements in mechanism for spot-proofing woolen, worsted, and other fabrics, which have, during finishing, received a luster.

By "spot-proofing" I mean a reduction of the luster to a degree which will, when water is sprinkled upon the dry face of a fabric, prevent its leaving dark spots or marks when the water has disappeared and the fabric shall have become dry again, where it had previously been rendered wet by the drops of water sprinkled upon it.

Heretofore, whenever spot-proofing has been attempted by the mills, it has been accomplished generally by steaming. The fabric, after having been finished in the regular way, was drawn a number of times over an open steam-box, such, for instance, as shown and described in my U. S. Patent Number 427069, May 6, 1890. This would remove from the finished heavy-weight cloths—like over-coatings, cloakings, certain classes of men's wear goods, etc.—such superfluous luster as would become spotted when water was dropped onto the fabric's face without impairing the handle of the goods too much. But, when passing light weight goods, like ladies' broad-cloth, or similar fabrics over an open steamer, the steam issuing from it would penetrate through the entire fabric with sufficient force and volume to remove not only the high luster on the face of the goods next the steamer, but it would take out of them also the remaining finish and handle, which the goods should retain in order to be acceptable to the trade. Therefore, the majority of light-weight fabrics would be, and still are, sent to the market with a full finish, so that they may handle satisfactorily; but they spot.

The object of my invention is to preserve the finish or at least, enough of it so the goods will handle acceptably to the trade, and yet remain proof against water marks.

Instead of putting steam to them, which goes clear through the goods and renders light-weight fabrics slimy and lifeless, be-

cause it robs them of practically all their finish, I apply hot water, and in such a manner as to skin off, as it were, merely the outermost film of the imparted luster and finish, that is, not enough to take the life out of the body of the goods, so that they will still handle substantial and fairly firm after the uppermost and superfluous luster has been soaked off the outer surface. In addition, because it does not pass through and out of the goods again like steam, the water will restore to the goods considerably more weight, which is taken out of them during finishing, and which, heretofore, the goods would regain only after lying a long time in cool and damp storehouses.

The invention consists in the improvements to be fully described hereinafter and the novelty of which will be particularly pointed out and distinctly claimed.

I have fully and clearly illustrated my invention in the accompanying drawings to be taken as a part of this specification and wherein—

Figures 1 and 2 represent opposite end views of so much of my machine as will enable those skilled in the art to understand the general principle of it, the cloth in Fig. 1 being in, and in Fig. 2 out of contact with the wetting-cylinder. Fig. 3 shows a front view of the entire face-wetting apparatus partly in cross section. Figs. 4 and 5 are details of the structure of Fig. 3, and Fig. 6 is a modification thereof. Fig. 7 shows an end view of a part of the machine with the cloth in contact with the wetting-cylinder, when the machine is in operation. Fig. 8 shows the end opposite to that of Fig. 7, with the cloth swung out of contact with the wetting-cylinder, and an apron drawn down between the two, when the machine is at rest; while Fig. 9 shows an enlarged detail thereof.

Referring to the drawings by characters of reference *a* represents the cloth being treated, the same running in the direction of the arrows through the machine and contacting either with a wet cotton wrapper 1, lapped around the outside of a hollow cylindrical metal shell 2 of the wetting-cylinder *D* as in Fig. 1, or not, as in Fig. 2. When contacting with the wrapper 1 the cloth passes under a roller *b* carried in a bracket *c* fast upon a three-armed segment *d* made preferably in two parts, that are bolted together and can swing upon the necks or jour-

nals *e* of the interior cylindrical heating body *f* arranged within the wetting cylinder and employed for maintaining a uniform temperature in the wrapper 1.

5 The segments *d* carry upon their sectional peripheries gear teeth *g* which mesh into pinions *h* keyed to a shaft *i*, extending across the machine and revolving in brackets *l* fastened to the main frames A. At one end 10 of the shaft *i* (Fig. 2) is keyed a spiral gear *m* meshing with another spiral gear *n* fast upon a shaft *o* having at its front end a handle *p*. This shaft *o* is revolubly mounted in a bracket *r* fast upon the post B of the 15 arched top frame C, and in a bracket *s* fast upon the cap *t*, on one of the bearings *v*, which are fastened to the front of the main frame A, and in which bearings *v* rest the necks or the journals *e* of the stationary interior heating cylinder *f* heretofore referred to. (Fig. 3.) Thus, when turning the 20 handle *p* the segments *d* will swing around the journals *e* of the interior stationary heating cylinder *f*. The shaft *o* carries also 25 a notched wheel or head *w* (see Fig. 3) and close to the bracket *s* and upon an extension *s'* of the bracket *s* swings a ball-arm *z* with a heavy ball *z'* at its end, which ball-arm has on its lower side a catch, or nose *y*, fitting 30 any of the notches in the periphery of the head *w*, so that, by first lifting the ball-arm *z*, high enough to disengage its nose or catch *y* from the notched head *w*, the operator, by 35 turning handle *p* can swing the segments *d* into any desired position and then lock them there, by dropping the ball-arm *z* with its catch *y* again into engagement with the notched head *w*.

As the cloth *a* is threaded between the rolls 40 *b'* and *b*, the operator when turning the handle *p* will swing it from the position shown in Fig. 1, to that shown in Fig. 2, the roll *b'* then holding the cloth high, so that it cannot flop down on to the wetting-cylinder D.

It will be seen that during the wetting operation the cloth passes over the upper surface of the wetting cylinder and is held in engagement therewith by the tension and guiding roll *b*, which is located on the upper face of the cloth, in which position of the segment the lifting member *b'* is beneath and out of contact with the cloth. When 50 the segments are rotated toward the rear of the machine the tension of the roller is lifted to relieve its pressure on the upper surface of the cloth, and the lifting member engages the under face of the cloth whereby the latter is lifted clear of the wetting cylinder and 55 moved over the same toward the rear of the machine so that such parts of the apparatus as are covered by the cloth during the wetting operation are made readily accessible.

60 Referring to Figs. 3 and 5, it will be noticed that there is a clearance, or slight air

space between the cylindrical metal shell 2, and the stationary interior heating cylinder *f*, so they cannot touch when the shell 2 is set in motion. Heating steam is admitted to the cylinder *f*, through the pipe *f'*, the water of condensation escaping through a siphon *f''* screwed into the extension *e'*, at *e''*, where there is a small pocket or chamber *e'''* to which is screwed a two-way elbow *f'''*. The cylindrical shell 2 carries at its ends 70 heads 3 which upon their necks carry rings 4 forming one-half of a set of ball-bearings, the other halves of which 5, fit into heads 6 fast upon the journals *e*, of the stationary heating-cylinder *f*. The heads 6 also have 75 end-thrust ball-bearings 7 inserted into them, so that if the machine should ever get 80 out of level, and the wetting-cylinder should lean toward one end or the other, the cylindrical shell 2 will still be able to revolve 85 freely and without any excessive degree of friction at its ends.

Directly below the wetting-cylinder D is placed a trough 8 resting upon the brackets 9 fastened to the main frame A. Bosses 10 are cast on the trough at its ends, which bosses have studs 11 screwed into them; and upon these studs swing bell-crank levers 12 which carry on their short upper arms a roll 13 while their longer, or lower arms are provided with weights 14. A stud shaft 15 carries a hand wheel 16 at the end and has a pinion 17 keyed to it, which meshes into a gear 18, fast upon a cam shaft 19, extending across the machine, with bearings in the 90 brackets 9 on the main frame. On this shaft 19 and directly under the bell-crank levers 12 are keyed cams 20, so that by turning the hand-wheel 16 the operator can swing the bell-crank levers 12 on the studs 11 so as to 95 raise them, and by so doing, can throw the roll 13 mounted in them out of contact with the wetting-cylinder D. Or, by turning the hand-wheel 16 still farther he can cause the 100 weighted bell-crank levers 12 to drop, so as 105 to bring the roll 13 into contact with cylinder D, and according to the number of weights 14 employed by him, it may press more or less hard against the cotton wrapper 1 lapped around the shell 2.

110 As the trough 8 is filled with water reaching high enough to touch the cotton wrapper 1 around the shell 2 of the wetting-cylinder D, this wrapper 1 can be made to absorb and carry up more or less water, the amount varying with the number of weights the operator chooses to hang on to the levers 12. There is placed in the bottom of this trough an overflow pipe 121, having two 115 openings on top, a higher one 122, and a lower one 123. Upon the opening 122 is screwed an adjustable crown, or level-ring 124, and upon the opening 123 may be placed a detachable cap, or shut-off 125. If the 120 wrapper 1 lapped around the shell 2 is a 125

long one, which causes the diameter of the wetting-roll to be correspondingly larger than when a shorter wrapper is used, the operator turns the crown 124 down a little and reduces thereby the level of the water in the trough, so that the larger diameter roll will dip no deeper into the water, than would a smaller diameter roll, built up with a shorter wrapper, in which latter case the 10 level-ring 124 would be screwed up correspondingly higher, to allow the same dip of roll into the water, as first had with a larger roll. After regulating the level of the water in this manner to let the overflow pass away 15 through 121, the cap 125 is placed upon the opening 123 during all the time the machine is in operation. When it is desired to stop it during the noon hour, or at any time during the day, the cap 125 is removed, where- 20 upon the level of the water will sink to the top of the opening at 123, that is to say, the water will cease to contact with the bottom of the wetting-cylinder and cannot fill it up with moisture at one point during this 25 time. The cam shaft 19 is then turned by the hand-wheel 16 to throw the roll 13 also out of contact with the wetting-roll body, whereupon the heat from the heating-cylinder f will soon dry the cotton wrapper 1. 30 When wishing to start up again to do some more spot-proofing, after the cotton wrapper has become dry, the cap 125 is put back once more upon the opening 123 until the 35 level of the water in the tank 8 shall have risen enough to flow over the upper edge of the level-ring or crown 124, that is to say, shall cause the cotton wrapper 1 to contact once more with the surface water in the tank. Then the wetting-cylinder has to be 40 revolved around a few times, to make the wrapper re-absorb the water, and to load it uniformly with it. The operator has to throw the roll 13 once more against it, which, 45 pressing evenly across its surface, squeezes all surplus water out of the wrapper 1 and insures a uniformly wet surface for the cloth a to lie up against when the machine is set in motion.

To turn the wetting-cylinder conveniently, 50 its metal shell 2 carries upon one end a gear-ring 21, the teeth of which match those cut into two small gears 22 made fast to two pinions 23 all of which turn loosely upon studs 24, projecting out from a bracket 25 fastened to the lower end of a sliding bar 26, moving vertically in a bracket 27 fastened to the post B over the main frame. 55 Centrally and horizontally mounted in the bracket 25 is a short shaft 28 having at one end a crank handle 29 and upon the other end a pinion 30 (Figs. 2 and 3) which meshes with the pinions 23. On top of the bracket 25 is a handle 31 for the operator to press down on, when he desires to push 60 the sliding bar 26 down into the position

shown in Fig. 3, or when he wishes to raise it to the position shown in Fig. 2. When pushing it down, as shown in Fig. 3, the gears 22 will mesh with the teeth of the gear-ring 21 upon the end of the cylindrical 70 shell 2 which, as soon as the handle 29 is turned will begin to revolve. A counter-weight 32 passing up and down through an opening in the bracket 27 and connected by a chain 33 (which runs over idlers 34 75 mounted in a bracket 35) to the sliding bar 26, permits the operator to push the gears 22 into and out of connection with the gear-ring 21 with the greatest ease. This apparatus for turning the wetting-cylinder is 80 not only a very convenient means when beginning to wet the wrapper 1 preparatory to starting the machine, but it is practically indispensable when a new wrapper has to be wound on to the shell 2 for the first time, 85 which, to insure a smooth padding, has to be done under a very considerable strain and tension. If I did not provide the means here described, the wetting-cylinder would have to be taken out every time, and placed in 90 some sort of winding apparatus, before a smooth covering could be properly put upon it.

The water for the tank 8 when first starting a machine, can be supplied by piping a 95 water connection to it, or it can be filled by pouring a few pails of water into it. Once filled the exhaust from the inner heating cylinder f is more than sufficient to keep it filled to overflowing, and to keep it also near the 100 boiling point at which temperature the water shows far greater avidity for soaking into the cloth than it does when it is cold. The exhaust, after reaching the two-way elbow f^3 when not wanted for heating the 105 water in the tank 8, in which case it passes into it through the pipe f^4 , can be turned away through the pipe f^5 , both of these pipes being provided with suitable valves for this purpose. 110

The tank 8 is provided in front and rear with guards 36 for confining the vapor arising from the hot water contained therein close to the wetting-roll D and preventing this vapor from spreading too much around the machine. 115

Referring to Figs. 7 and 8, of the drawings, I have shown there the manner of handling the cloth, as it goes to the wetting-cylinder D. In passing from the cradle E 120 upward the cloth a travels over and under two round stationary bars 37, which form the ties for a couple of trolley trucks 38 running freely upon a pair of rocking-rails 39, one at each end of the machine, and located directly under a couple of overhead arms F fast upon the tops of the post B secured to the main frames A of the machine. The rails 39 near one end are pivotally connected at 41 with hangers 40 de- 130

pending from the overhead arms F and at the other end they are shackled to links 42 pivotally connected to crank-arms 43, which are fastened to a shaft 44, which extends 5 across the machine and carries upon one end a hand-wheel 45, by turning which the rails 39 may be raised from the position shown in Fig. 7 to that shown in Fig. 8, and vice versa. The links 42 have semi-circular 10 notches 46 cut into them, which fit the round shaft 44 when the links are swung upward, and as in Fig. 8 a little beyond their vertical central line, so as to lock them in that position. When thus raised into this 15 position, the trucks 38 upon the rails 39 will roll down the incline until one of the truck wheels will abut against the stop 47 and arrest it, whereas, if the hand-wheel is turned to lower the links 42 into the position shown 20 in Fig. 7 the trucks will roll back again.

When the machine is running, as shown in Fig. 7, and the operator desires to stop it, he first swings the segments d into the position shown in Fig. 8, and then, by turning 25 the wheel 45 overhead, causes the trucks 38 to roll back until they strike the stops 47. As the cloth α is hugging closely around the stationary bars 37 the cloth will cling to them during their retreat from the position 30 shown in Fig. 7, and thus the loose loop of cloth which would form and hang down between the segments, when they are thrown up, and the truck-bars overhead, if they remained fixed in the position shown in Fig. 35 7, is taken up as fast as the automatically retreating trucks can travel. The weight of the trucks and the momentum they gain thereby in their downward travel is such as to take care of the loose fold of cloth that 40 might otherwise hang down over the operator's head when the segments are turned up in order to free the cloth α from contact with the wetting-cylinder D. The operator is thus not annoyed when standing between the 45 cradle E, and the front of the wetting-cylinder D by a bag of cloth coming down and enveloping him, and thus seriously interfering with his work every time he wishes 50 to break contact of the cloth with the wetting-cylinder.

When the operator, for whatever reason, has to stop the machine with the cloth threaded as shown, and removed from contact with the wetting-cylinder, the vapor 55 rising from the bared portion of the wetting-cylinder would, in a very short time, cause that portion of the cloth lying in close proximity thereto to become darker in shade, than any other portion of the cloth, already 60 past the cylinder D, or yet to pass over it. To prevent such shading I employ preferably a rubber covered apron 48, rolled upon a roller 49, which is mounted in a bracket 50, and draw the same whenever the machine 65 has to stop, between the cloth, after the

cloth has been raised away from the cylinder D, and the cylinder. At the lower end of the curtain is attached a flat metal bar 51 of sufficient weight to keep the apron taut when drawn down, as shown in Figs. 8 and 70 9. At each end of it is a U-shaped channel-piece 52 for guiding the ends of the curtain bar, a bracket 53 fast upon the gird A' holding it rigidly at the proper angle, so that the curtain shall touch neither the cloth nor the 75 cylinder D but will form an effective shield between the two to prevent any of the vapor from the bared cylinder D reaching the cloth.

While in Figs. 1 and 2 I have shown but 80 two rolls, b and b', mounted in bracket c attached to the segments d, I have added a third one c², as shown in Figs. 7, 8 and 9, to enable me to thread the cloth in two different ways, one of which gives more and 85 the other giving less friction to the cloth at that point, as the case may require.

In Fig. 6 I have shown a modification in which cloth may be treated which requires a greater amount of loading with water 90 than ordinarily demanded, in which form a roller 13' mounted in a swinging lever 12' weighted at one end as at 14' contacts with the wetting roll, and receives from it such moisture as has not been absorbed by the 95 cloth passing over it before contacting with the roller 13', which roller 13' is pressed against the wetting roll by the weights 14'. By its contact with the wetting roll D it is not only revolved in a direction opposite to 100 that in which the cloth runs, but it gathers moisture from the roll D and deposits the same upon the cloth thereby adding not only additional moisture but wiping the moisture previously received by the cloth by contact 105 with the roller D into the surface of the cloth, thus causing the cloth to take up more water than it would were the roll 12' omitted.

It is obvious that the covering of the wetting material being of absorbent material that it will still contain some of the moisture taken up after it has passed the cloth, and that some of this remaining moisture will be collected by the roller 13' and transferred to the part of the cloth which has 115 passed the wetting cylinder.

Having thus described my invention, what I desire to secure by Letters Patent is:

1. In combination, a cloth-treating roll, a cloth-guiding member in advance of the cloth-treating roll and arranged to have the cloth pass over the same to the cloth-treating roll, and means for swinging the guiding member over and rearward of the treating roll. 120
2. In combination, a cloth treating roll, a tank receiving the lower surface of said roll, means for tensioning and guiding a strip of 125 130

cloth in contact with the upper surface of said roll, means for lifting the cloth out of engagement with the roll, and means for relieving said tensioning means, and simultaneously operating said lifting means.

5 3. In combination, a cloth treating roll, means for guiding a strip of cloth in contact with said roll, a tension member coöperating with the outer surface of the cloth to hold the same in contact with said roll, a lifting member adapted to coöperate with the under side of the cloth, and means for simultaneously operating said members to relieve the tension and to positively lift the cloth by the lifting member out of contact with the cloth treating roll.

10 4. In combination, a cloth treating roll, members fulcrumed concentric with the axis of the roll, a cloth engaging element connected to said members and extending longitudinally of said roll, a segmental rack connected to said members, an operating shaft, and a gear on said shaft meshing with the said segmental rack.

15 5. In combination, a cloth treating roll, gear members pivoted concentric with said roll, a supporting frame operated by the gear members and extending outside the circumference of the roll, a tension member and a lifting member supported by said frame, and between which the cloth passes to said cloth treating roll, said members being parallel to said roll, and gearing for swinging said gear members to operate said tension and lifting members.

20 6. In combination, a cloth treating roll, a pivoted frame, a tension member carried by the frame and operating in one position of said frame to hold the cloth adjacent to the cloth treating roll, and a lifting member carried by the frame and arranged to be out of engagement with the cloth when the latter is held against the cloth treating roll, and means for moving said frame over the cloth treating roll to relieve the cloth from the holding member, and lift it by said lifting member out of engagement with the cloth treating roll.

25 7. A machine for the purpose set forth, comprising an imperforate hollow roll having a covering of absorbent material, means for saturating said covering with liquid, said means comprising, a tank adapted to hold a liquid into which said roll projects directly to be saturated by said liquid, a roll for squeezing liquid from said absorbent covering, and means for determining the degree of pressure of the said second roll for regulating the amount of liquid to be carried by said absorbent covering.

30 8. A machine for the purpose set forth, comprising an imperforate hollow roll having a covering of absorbent material, means for saturating said covering with liquid, said means comprising, a tank adapted to

hold a liquid into which said roll projects directly to be saturated with said liquid, a roll for squeezing liquid from said absorbent covering, means for determining the degree of pressure of the said second roll 70 for regulating the amount of liquid to be carried by said absorbent covering, and means for heating the liquid while in the tank.

9. A machine for the purpose set forth, 75 comprising an imperforate hollow roll having a covering of absorbent material, means for saturating said covering with liquid, said means comprising, a tank adapted to hold a liquid into which said roll projects 80 directly to be saturated with said liquid, a roll for squeezing liquid from said absorbent covering, means for determining the degree of pressure of the said second roll for regulating the amount of liquid to be 85 carried by said absorbent covering, means for admitting a heating vapor to and exhausting it from said hollow roll and a connection between the exhaust and the tank for discharging the exhaust vapor into the 90 tank to heat the liquid therein.

10. In combination, a cloth treating roll, a pair of cloth guiding rolls between which the cloth passes to the cloth treating roll, one of said rolls operating to hold the cloth in engagement with the cloth treating roll, and means for moving said guiding rolls away from the cloth treating roll so that the other of said guiding rolls lifts the cloth 95 out of engagement with the cloth treating 100 roll.

11. In combination, a cloth treating roll, a rotatable cloth guiding roll in advance of the cloth treating roll and arranged to have the cloth pass over the same to the cloth 105 treating roll, and means for swinging the guiding roll over and rearward of the treating roll to lift the cloth clear of the treating roll.

12. In combination, a cloth treating roll, 110 a frame pivoted concentric with the cloth treating roll and having a part extending in advance of the cloth treating roll, a tension member and a lifting member carried by said part and between which the cloth passes to the cloth treating roll, and means for swinging said frame over and rearward of the cloth treating roll to simultaneously relieve the tension on the cloth and lift it free of the cloth treating roll.

13. In combination, a revoluble imperforate wetting-roll having a covering of absorbent material, a heating chamber within the roll and about which said roll revolves, said chamber being closed to the interior of the wetting-roll, a steam pipe opening into said chamber, exhaust means for the chamber, and means external to said wetting-roll for applying liquid to the outer surface thereof.

14. In combination, a revoluble imperforate wetting-roll, a heating chamber within the said roll and about which said roll revolves, said chamber having an opening in one end, a steam pipe entering said chamber through said opening, exhaust means for the chamber, and means external to said wetting-roll for applying liquid to the outer surface thereof.
15. In combination, a revoluble imperforate wetting-roll, a heating chamber within said roll and having hollow journals upon which said roll revolves, a steam pipe entering said chamber through one of said hollow journals, exhaust means for the chamber, and means external to said wetting-roll for applying liquid to the outer surface thereof.
16. In combination, a fixed closed chamber, a wetting roll inclosing said closed chamber, and revoluble about the same, admission and exhaust means for said closed chamber, and end thrust and radial bearings between the closed chamber and the roll.
17. In combination, a cloth treating roll, means for positively moving the cloth out of contact with the roll, and means for automatically and simultaneously taking up the slack in the cloth when so moved.
18. In combination, a cloth treating roll, means for moving cloth out of contact with the roll, and means for automatically taking up the slack in the cloth, comprising a track and a tension carriage traveling on said track.
19. In combination, a cloth treating roll, means for moving cloth out of contact with the roll, and means for automatically taking up the slack in the cloth, when the cloth is moved out of contact with the roll, comprising an inclined track and a gravitating tension carriage on said track.
20. In combination, a cloth treating roll, means for moving cloth out of contact with the roll, means for automatically taking up the slack in the cloth comprising an inclined track and a gravitating tension carriage on said track, and means for changing the direction of inclination of the track.
21. In combination, a cloth treating roll, means for moving the cloth out of contact with the roll, and a guard movable between the cloth and roll when the cloth is away from the roll.
22. In combination, a cloth treating roll, means for moving the cloth out of contact with the roll, and a guard movable between the cloth and roll when the cloth is away from the roll, said guard consisting of a flexible apron.
23. In combination, a cloth treating roll, means for moving the cloth out of contact with the roll, and a guard movable between the cloth and roll when the cloth is away from the roll, said guard consisting of a flexible apron.
24. In combination, a cloth treating roll, means for taking up slack in the cloth consisting of a pivoted trackway, means for swinging the trackway to change its direction of inclination, and a traveling tension device movable along said trackway.
25. In combination, a cloth treating roll, means for taking up slack in the cloth consisting of a pivoted trackway, a shaft, means connecting the shaft and trackway whereby rotation of the shaft changes the direction of inclination of the trackway, and a traveling tension device movable along said trackway.
26. In combination, a cloth treating roll, means for taking up slack in the roll consisting of a pivoted trackway, a shaft, a link connecting the trackway and the shaft whereby the rotation of the shaft changes the direction of inclination of the trackway, and a traveling tension device movable along said trackway.
27. In combination, a cloth treating roll and driving means for the roll vertically movable toward and away from the roll, and means for balancing said driving means.
28. In combination, a cloth treating roll, and driving means for the roll consisting of a frame movable toward and away from said roll, gearing on the frame adapted to engage the roll, and balancing means for said frame and gearing.
29. In combination, a cloth wetting roll, a tank into which said roll projects, adapted to hold a liquid to wet the roll, and means for determining the extent of the surface of the roll to be wetted by said liquid, said means consisting of an overflow device having an adjustable inlet, and an auxiliary inlet below the first inlet, and a closure for the auxiliary inlet.
30. In combination, a wetting roll, a presser roll engageable with said wetting roll, arms in which said presser roll is journaled, weighted arms connected to said first-named arms, a shaft and eccentrics on said shaft and engageable with the said last-named arms to move the presser roll relative to the wetting roll against the force of the weighted arms.
31. In combination, a wetting roll, a tank into which the said roll projects, means for heating water in said tank, and a guard plate extending from one edge of the tank to a point adjacent the surface of the roll and beneath the cloth engaging surface thereof.
32. In combination, a chamber having axial extensions, bearing plates on said extensions spaced from the ends of the chamber, a roll surrounding said chamber between said plates, and bearings for said roll between the ends of the roll and said plates.

33. In combination, a chamber having axial extensions, bearing plates on said extensions spaced from the ends of the chamber, a roll surrounding said chamber between 5 said plates, and having flanges extending between said plates and the end of the chamber, and radial and end thrust bearings between the said flanges and said plates.

34. In combination, a wetting roll adapted to have cloth pass over the same in contact therewith, and a moisture collecting roll in engagement with the wetting roll and adapted to engage the cloth after passing the wetting roll.

35. In combination, a wetting roll adapted to have cloth pass over the same in contact therewith, and a moisture collecting roll in engagement with the wetting roll and adapted to engage the cloth after passing

the wetting roll to transfer moisture from 20 the wetting roll to the cloth, and means for urging said second roll yieldingly against the wetting roll.

36. In combination, a cloth-wetting roll, 25 means for heating the roll, means for passing the cloth in contact with the roll, means for moving the cloth out of contact with the roll, and a guard protecting the cloth from vapor from the roll when the cloth is out of contact with the roll.

In testimony whereof I have signed my name to this specification in the presence of two subscribing witnesses.

DAVID GEESNER.

Witnesses:

M. E. McNINCH,
C. G. HEYLMUR.

Copies of this patent may be obtained for five cents each, by addressing the "Commissioner of Patents, Washington, D. C."

It is hereby certified that in Letters Patent No. 1,157,773, granted October 26, 1915, upon the application of David Gessner, of Worcester, Massachusetts, for an improvement in "Spot-Proofing Mechanism," errors appear in the printed specification requiring correction as follows: Page 2, line 31, for the compound word "bell-arm" read *ball-arm*; page 5, claims 7, 8, and 9, line 5, after the word "comprising" strike out the comma; and that the said Letters Patent should be read with these corrections therein that the same may conform to the record of the case in the Patent Office.

Signed and sealed this 23rd day of November, A. D., 1915.

[SEAL.]

J. T. NEWTON,
Acting Commissioner of Patents.

Cl. 26—7.
